UNITED STATES PATENT OFFICE.

RICHARD N. ROBERTS, OF ROCKVILLE, CONNECTICUT.

DENTAL-COTTON-PELLET MACHINE.

SPECIFICATION forming part of Letters Patent No. 451,701, dated May 5, 1891.

Application filed March 10, 1891. Serial No. 384,419. (No model.)

To all whom it may concern:

Be it known that I, RICHARD N. ROBERTS, of Rockville, in the county of Tolland and State of Connecticut, have invented certain new and 5 useful Improvements in Dental-Cotton-Pellet Machines, of which the following is a full, clear, and exact description, whereby any one skilled in the art can make and use the same.

My invention relates to the art or profession 10 of dentistry, and particularly to a device by the use of which pellets of fibrous material, usually cotton, such as are used in the preparation of teeth for filling and in other surgical dentistry, may be quickly and rapidly 15 formed. The old practice in this regard has been to take up with a pair of gold forceps or a like tool a small quantity of cotton fiber and roll it up between the fingers to form a small pellet most commonly used for drying 20 out a cavity in a tooth preparatory to filling the excavation; and my invention consists in a device by means of which such a pellet may be quickly and rapidly formed by the use of mechanism; and it further consists in details 25 of the several parts making up the apparatus as a whole, as more particularly hereinafter described, and pointed out in the claims.

Referring to the drawings, Figure 1 is a detail view in side elevation of part of the device 30 shown as clamped to a table or like support and illustrating the method of using the device. Fig. 2 is a detail view, in central vertical section, of the device. Fig. 3 is a detail top or plan view of the device. Fig. 4 are views of the pellet after removal from the 35 forceps and while held in the forceps.

In the accompanying drawings, the letter *a* denotes a brush-support, preferably a disk-shaped piece of metal arranged in a horizontal 40 position on a support that enables the disk to be rotated. The disk is preferably slightly dished on its upper surface and has at or near the center a holding-point *b*, that is usually a slight indentation or depression, into which 45 the end of a pair of gold forceps or other tool adapted to hold a wisp of cotton or like fiber will easily fit. At one side of the center about which the disk or brush-support turns, and adjacent to the holding-point, is secured 50 a wiper or brush *c*, and there may be one or more such brushes. The brush is preferably made of bristles, the ends of which are so ar-

ranged as to wipe or comb the fibers of cotton as the disk is rotated.

In the form of device in which my invention is embodied, as shown in the drawings, the disk is mounted on a stem *d*, that projects upward from a tubular standard *e*. The stem *d* is provided with a spiral groove or thread *d'*, and it passes through a nut *f*, fast in the top of the standard, and is secured to the lower end of a coil-spring *g*, the upper end of which is secured to the walls of the standard, as at *e'*. This standard is preferably secured to a cotton-holder *h* in such manner that the disk stands in a substantially horizontal position.

The operation of the device is as follows: A small quantity of cotton fiber *i* is grasped in a pair of gold forceps, and the point of the latter inserted in the holding-point *b* with a downward pressure that thrusts the stem *d* into the standard against the holding power of the coil-spring *g*. This downward movement of the disk causes it to rotate, as the nut is fixed against rotation and the thread on the nut and on the stem correspond and are interengaged. As soon as the pressure on the disk is removed it is at once returned to its uppermost position by the recoil of the spring.

The purpose of making the disk rotate is to cause the wiper or brush to wind the fibers of cotton around the points of the forceps or other tool that holds the fibers and form a pellet, and the latter will of course depend in size upon the quantity of fiber that is taken up at any one time. The pellet that is formed is made entirely by the use of the mechanism, and by mounting the disk upon a reciprocating stem the whole operation of forming the pellet may be accomplished with one hand, that holds the dental forceps in a position as shown in Fig. 1 of the drawings.

It is obvious that it is not essential to the invention that the disk be given any depthwise motion, as the rotary motion is all that is required in the operation of forming the pellet, and the invention is not limited to a device in which the disk has the depthwise motion, but is present, provided the disk has the wiper or brush and the rotary motion and the means for rotating the disk.

The standard is secured to a cotton-holder

simply for the purpose of convenience, and it may be provided with clamping means for securing it to any fixed object in position convenient for use. The fiber commonly used in dentistry for this purpose is of cotton; but it is obvious that other fiber may be used in connection with this device without departing from the invention.

It is obviously not essential to the invention that the brush-support should be of disk shape; but the form shown is preferred, for the reason that it serves to guide the point of the forceps quickly to the center about which the brush is revolved, and this is of particular advantage when but one hand can be used in operating the device.

I claim as my invention—

1. In combination with a supporting-standard, a rotary brush-support and a brush secured to the support eccentric of the center on which the support rotates, substantially as described.

2. A cotton-pellet-forming device comprising a rotary brush-support having a holding-

point, and a brush or rubber arranged at the side of the holding-point, all substantially as described.

3. In combination with a supporting-standard, a disk having a holding-point, and a brush located eccentric to the point on the upper surface of the disk, a reciprocating and rotary stem supporting the disk on its upper end and means whereby the stem and disk are rotated, all substantially as described.

4. In combination with a supporting-standard, a rotary brush-support with a holding-point, a brush located eccentric to the center on which the support rotates, the stem with the spiral thread to which the brush-support is secured, the nut fixed to the standard and through which the stem passes, and the coil-spring attached at one end to the standard and at the other to the stem, all substantially as described.

RICHARD N. ROBERTS.
